(57) **CLAIM**

The ornamental design for a gondola adaptor shelf system, as shown and described.

DESCRIPTION

FIG. 1 is a front elevational view of a gondola adaptor system showing a first embodiment of my design.

FIG. 2 is top, front and left side perspective view thereof.

FIG. 3 is an enlarged fragmentary top, front and left side perspective view thereof with portions of the adaptor system being omitted for clarity of illustration and with the broken line disclosure of a portion of merchandise gondola being for illustrative purposes only and forming no part of the claimed design.

FIG. 4 is a reduced top, front and left side perspective view of a merchandise gondola, the broken line disclosure being for illustrative purposes only and forming no part of the claimed design.

FIG. 5 is a reduced top, front and left side perspective view of a second embodiment of a gondola adaptor shelving system showing my new design, with the broken line disclosure of a gondola being for illustrative purposes only and forming no part of the claimed design.

FIG. 6 is a reduced top, front and left side perspective view of a merchandise gondola, the broken line disclosure being for illustrative purposes only and forming no part of the claimed design; and,

FIG. 7 is a reduced top, front and left side perspective view of a third embodiment of a gondola adaptor shelving system showing my new design, with the broken line disclosure of a gondola being for illustrative purposes only and forming no part of the claimed design.
